United States Patent Office

Des. 191,712

191,712

CLOCK OR SIMILAR ARTICLE

Robert Darr Wert, Gill, Mass., assignor to General
Electric Company, a corporation of New York

Filed May 8, 1961, Ser. No. 65,064

Term of patent 7 years

(Cl. D42-7)

BEST AVAILABLE COPY

The figure is a front perspective view of a clock embodying my new design.

The rear of the clock is conventional, and the side and end not shown are the same as the side and end shown. The essential features are shown in full lines.

I claim:

The ornamental design for a clock or similar article, substantially as shown and described.
